UNITED STATES PATENT OFFICE

GABRIEL CHRISTIAN ERASMUS KEET, OF KLERKSDORP, TRANSVAAL, SOUTH AFRICA

MEANS FOR REDUCING FRIABLE MATERIALS

Application filed August 22, 1929, Serial No. 387,744, and in the Union of South Africa June 27, 1929.

This invention has for its object to provide an improved means for reducing friable materials by combined grinding and crushing operations, which will be particularly suitable for the reduction of ores and the like.

According to the invention, the material is fed into a mill comprising two complementary grinding rolls, one of which is subjected to a continuous oscillation in the direction of the other.

The nature of the invention is hereinafter more particularly described with reference to the accompanying drawings, wherein Figs. 1 and 2 are diagrammatic views showing respectively in plan and elevation one embodiment of the invention as applied to a mill for reducing ores and the like.

Referring to the drawings, 3 and 4 indicate two grinding rolls, of which the working faces are respectively of concave and convex section. The roll 3 has formed in its periphery a V-groove 5, whilst the roll 4 is provided with a peripheral rim 6 of inverted V-shape, the angle included by the sides of the V-groove 5 of the first roll, hereinafter termed the female roll, being equal to that included by the sides of the rim 6 of the second roll, hereinafter termed the male roll.

It is preferable that the diameters of the two rolls should be unequal, as shown.

It is preferable that the diameters of the two rolls should be unequal, as shown.

The female roll 3 is revolubly mounted in suitable bearings 7 and driven by any convenient means, e. g., the gearing 8^a from the driving shaft 9. The male roll 4 is revolubly mounted in bearings carried by the free ends of two rocking levers 10 which are connected by suitable links and levers with an eccentric 11 mounted upon the driving-shaft 9, the arrangement being such that rotation of the eccentric 11 operates to oscillate said rocking levers 10, thus moving the male roll 4 alternately towards and away from the female roll 3.

Conveniently, the free end of the eccentric rod 11^a may be connected to a second lever 12 having connected thereto a link 13 pivotally connected to the mid-point 14 of a tog-

gle mechanism 15, 16, of which one member 15 is pivoted to the free ends of the rocking levers 10 and of which the other member 16 is secured to the end or ends of one or more spring-pressed abutments 18, in such manner that the stroke of the eccentric 11 is transmitted to the said link 13 which operates the toggle levers 15, 16, to oscillate the rocking levers 10, the spring-pressed abutments 18 being arranged to take up the thrust of the oscillatory motion, whilst also serving as shock absorbers in the event of unusually hard substances being fed into the mill.

Means may be provided for regulating the stroke of the oscillatory roll 4, whilst the mill is in operation, e. g., the fulcrum 20 of the lever 12 to which the eccentric rod 11 is connected may be adjustably mounted in such manner as to permit of regulation of the throw of said lever 12. Conveniently the fulcrum 20 is slidably mounted with relation to the lever 12 as shown, its position being regulated by an adjusting screw 21. If desired, said fulcrum 20 may be adapted to be moved up to the point of connection 22 of the toggle link 13 with said lever 12, whereby the oscillating action imparted to the toggle mechanism 15, 16, may be discontinued, if desired.

In the female roll 3, the groove 5 between the two grinding faces is deepened sufficiently at 5^a to prevent "bottoming" of the rim 6 of the male roll 4, thus ensuring that the grinding faces of the latter contact properly with those of the female roll 3, and so causing the faces of the two rolls to wear evenly.

In operation, material to be reduced is fed continuously by a suitable jiggling conveyor or like feed (not shown) between the grinding faces of the two rolls where the combined crushing and grinding motion effectively reduces the material to a very fine state. The reduced material then falls upon a screen (not shown) where there is provided suitable means for removing any insufficiently reduced particles and returning them to the feed of the mill, thereby ensuring a complete disintegration of the material.

What I claim as my invention and desire to secure by Letters Patent is:—

1. Means for reducing friable materials, comprising two complementary grinding rolls the working faces of which are respectively in the form of a V-groove and a rim of inverted V-shape, means for rotating the first roll, the second roll being rotatably mounted in the free ends of suitable rocking levers and means for oscillating said rocking levers continuously in the direction of the other roll.
- 10 2. Means for reducing friable materials, comprising two complementary grinding rolls, the working faces of which are respectively in the form of a V-groove and a rim of inverted V-shape, means for rotating the first roll, the second roll being rotatably mounted in the free ends of suitable rocking levers, and an eccentric mounted upon the driving shaft and connected to said rocking levers.
- 15 3. Means for reducing friable materials, comprising two complementary grinding rolls, the working faces of which are respectively in the form of a V-groove and a rim of inverted V-shape, means for rotating the first roll, the second roll being rotatably mounted in the free ends of suitable rocking levers, an eccentric mounted upon the driving shaft and connected to said rocking levers, and means for regulating the stroke of the rocking levers.
- 20 4. Means for reducing friable materials, comprising two complementary grinding rolls, the working faces of which are respectively in the form of a V-groove and a rim of inverted V-shape, the V-groove of the first roll being deepened to prevent "bottoming" of the rim of the second roll, and means for continuously oscillating the second roll in the direction of the other.
- 25 5. Means for reducing friable materials, comprising two complementary grinding rolls of which the working faces are respectively of concave and convex section, the second roll being rotatably mounted in the free ends of rotating levers, and eccentric, a toggle mechanism the mid-point of which is connected to said eccentric, one member of said toggle mechanism being connected to the free ends of said rocking levers whilst the other member is provided with spring-pressed abutments.
